(57) **CLAIM**

We claim the ornamental design for a camera stand, as shown and described.

DESCRIPTION

FIG. 1 is a perspective view of a camera stand of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof; and,

FIG. 8 is a front view with the top portion moved thereof.

The broken line showing of camera stand is included for the purpose of illustrating environment and forms no part of the claimed design. Additionally, the unevenly broken lines in the drawings define the limits of the claimed design.
